UNITED STATES PATENT OFFICE.

THEODORE H. NELSON, OF CHICAGO, ILLINOIS.

LOCKOUT MECHANISM FOR INTERCOMMUNICATING TELEPHONE SYSTEMS.

1,419,403.

Specification of Letters Patent. Patented June 13, 1922.

Application filed October 21, 1918. Serial No. 259,019.

To all whom it may concern:

Be it known that I, THEODORE H. NELSON, a citizen of the United States, residing at Chicago, in the county of Cook and State of Illinois, have invented a certain new and useful improvement in Lockout Mechanisms for Intercommunicating Telephone Systems, of which the following is a specification.

My invention relates to an improved lock-out mechanism adapted particularly for use with intercommunicating telephone systems by which when one of the lines of the system is connected with another line for conversation, it is impossible to actuate selecting and switching mechanism at a third station to connect the line of said third station with either of the busy lines. More specifically, my invention consists of a combined selecting, switching and lock-out mechanism provided with releasing devices by which, after using a desired connection, when the receiver is placed on the switch hook of either of the connected stations, the associated selecting and switching mechanism is restored to neutral condition. In this respect my present invention constitutes an improvement on the invention disclosed in United States Letters Patent #1,290,645, which were issued to me January 7, 1919, which shows releasing mechanism of the kind referred to, but no lock-out mechanism.

My invention, as described below, is equally applicable to systems employing either two wire lines or three wire lines and the present invention includes the system of either kind of which the lock-out mechanism is a part as well as the lock-out mechanism itself. My invention will best be understood by reference to the accompanying drawings showing preferred embodiments thereof, in which

Fig. 1 is a diagrammatic view of a three-wire system involving my improved lock-out mechanism,

Fig. 2 is a vertical sectional view of the lock-out mechanism employed in the system of Fig. 1,

Fig. 3 is a front elevation of the mechanism shown in Fig. 2,

Fig. 4 is a sectional view of the parts shown in Fig. 2 taken along the line 4—4 in Fig. 2,

Fig. 5 shows in a view similar to Fig. 1, a two-wire system involving my invention and

Fig. 6 is a detail sectional view of the

modification required in the mechanism shown in Figs. 2, 3, and 4 to adapt it for use in the system shown in Fig. 5.

Similar numerals refer to similar parts throughout the several views.

Referring to Figs. 2, 3 and 4, my lock-out mechanism consists of a casing 10 having a removable front plate 11, to which the switching and lock-out mechanism is secured. Centrally disposed in the front plate 60 is a plunger 12, to the outer end of which a dial 13 is secured. The dial is contained in a cylindrical recess formed by an annular flange 14 projecting from the front plate and may be rotated to select a desired line 65 and then moved longitudinally of the plunger to first test for a busy line and automatically operate the lock-out mechanism if the desired line is busy thereby preventing further movement of the plunger to connect 70 with the desired line, second to connect with the desired line if it is not busy, and third, by continued movement to send ringing current over the connected line. The dial is normally held in its outer or neutral position by a spring 15 and motion to connect the lines is prevented unless the dial is in proper angular position, by a rearwardly projecting pin 16 carried by the dial and co-operating spaced holes 17 in the front plate 80 arranged angularly relatively to the line contacts so that longitudinal motion of the plunger is permitted only when the dial is in an angular position bringing the connecting switch blades and the line contacts into 85 alignment.

The front plate 11 has secured thereto and projecting rearwardly therefrom, posts 18 which support at their rear ends a contact plate 19 of insulating material held in place 95 on said posts preferably by spring catches 20 or equivalent means, so that the contact plate may be readily removed from said posts and front plate to permit the contact plate to be wired into the system when it is 100 installed, without requiring the installation at the same time of the front plate and the mechanism carried thereby, which need not be done until the system is ready for testing. The contact plate is in effect a terminal plate 105 of the system for each station, and has mounted thereon a set of contacts 21 for each line of the system, there being three of these contacts in each set, and three contact rings 22, 23 and 24 for connection with the line 110

and circuits of the station where the switching mechanism is located. The inner end of the plunger 12 has secured thereto and insulated therefrom, three switch blades 25, 26 and 27 for connecting the rings 22, 23 and 24 respectively with the outer, the middle and the inner line contact 21 of any desired set, when the plunger is pushed inwards. The plunger has rigidly secured thereto, a disk 28, for actuating through insulating blocks the contact springs 29, 30 and 31, which are mounted upon and insulated from the front plate. The contact spring 29 is placed under tension for the neutral position of the plunger by the action of the spring 15, and when the plunger is pushed in, said contact spring follows said inward movement to first engage the contact spring 32 which is in engagement with the contact 33, and to then move the spring 32 from engagement with the spring 33. Inward movement of the plunger also moves the spring 30 to engage the contact spring 34 and at the end of said inward movement, the spring 31 is moved to engage the contact spring 35. The contact springs 32, 33, 34 and 35 are mounted upon and insulated from the front plate in operative relation to the springs 29, 30 and 31 to secure the results described. A pivoted latch 36 rests upon the disk 28 to engage said disk in the line connecting position of the plunger to prevent outward movement of said plunger and the parts carried thereby during a conversation. Said latch forms the armature of the releasing magnet 37, carried by the front plate, and is pivotally connected to the yoke of said magnet at 38. The plunger 12 carries adjacent the disk 28, a sleeve 39 rotatable on said plunger but prevented from moving longitudinally thereon by a pin 40 in said plunger. The rear end of said sleeve has an upwardly projecting arm 41 extending through a slot 42 (shown in Fig. 4) in the rear end of the latch 36. Said arm has extending through its upper end a pin 43, in a plane above lugs 44 projecting upwardly from the latch 36, when said latch is in its lower position. When said latch is in its upper position however, said lugs lie in the path of the pin 43 and prevent movement of the plunger rearwardly a sufficient distance to bring the switch blades 26 and 27 into engagement with the corresponding contacts 21 and rings 23 and 24, if the plunger were in its neutral position at the time of raising said latch.

The parts described are so proportioned and related that a small movement of the plunger inwards from its neutral position, results in closing the contact springs 29 and 32 and at the same time connecting the outer contact 21 with the ring 22. The ring 22 and contacts 29 and 32 are connected with the magnet 37 in a manner to be described

such that if at this time battery potential is on the outer contact 21, the magnet is energized and the latch 36 is at once raised to prevent further inward movement of the plunger by the engagement of the pin 43 against the lugs 44. If the outer contact 21 is free from battery potential, the plunger may be moved further inwards to bring the switch blades 26 and 27 into engagement with the corresponding contacts to connect the lines for conversation in a manner to be described, and at the same time the lug 45 on the latch 36 drops in front of the disk 28 to prevent disconnection of the lines until the latch is raised. The contacts 30 and 34 may be closed at any time as long as they are closed when the plunger is in its position to connect the lines for conversation. At this time the contacts 31 and 35 are still open and may be closed by further inward movement of the plunger after which upon releasing the pressure on the plunger, the spring 15 moves the plunger outwards to its locked-in position again opening the contacts 31 and 35. This is to provide for ringing the called line in a manner to be described. At the end of a conversation, the magnet 37 is energized by the operation of the corresponding hook switch in a manner to be explained and the latch 36 is raised freeing the plunger which, under the action of the spring 15, is thereupon restored to its neutral position together with the parts carried thereby.

In the system shown in Fig. 1, three stations are shown which represent any three stations of the system, for example stations 3, 4 and 5, and for each station line wires extend through the system as shown at L³, L⁴ and L⁵, each line being of the three wire type. As the stations are the same and connected in the same manner to the system it will be necessary to describe but one of them, as for example, the station 4 and the connections made to its line wires L⁴. The terminals 1 and 2 of the telephone set are connected with one terminal of the impedance windings 46 and 47, the other terminals of which are connected with the terminals 4 and 3 respectively of the telephone set. The terminal 3 is also connected with one terminal of the signal bell 48 by wire 49, with one terminal of the primary winding 50 of the induction coil by wire 51, and with the contact spring 35 of the switching mechanism by wire 52. The terminals 4, 5, 6 and 7 are connected by wires 53, 54, 55 and 56 respectively, with springs 57, 58, 59 and 60 of the hook switch. The terminal 5 is also connected by wire 61 with the spring 31 of the switching mechanism and this wire is connected by wire 62 with one terminal of the magnet 37. The other terminal of the primary winding 50 is connected with one terminal of the transmitter 63, the other ter-

5 minal of which is connected by wire 64 with the spring 65 of the hook switch. The 10 spring 66 of the hook switch is connected by wire 67 with the other terminal of the bell 48 and this wire is connected by wire 68 with the contact spring 34 of the switching mechanism. The secondary winding 69 of the 15 induction coil has its terminals connected with the terminals of the receiver 70. The 20 construction of the hook switch is such that with the receiver on the hook 71, the springs 59 and 66 engage each other and all the other springs are out of engagement with the adjacent springs, and when the hook 71 is in 25 its upper position as a result of removing the receiver from the hook, the springs 59 and 60 are in engagement with each other, the springs 57, 58 and 65 are in engagement with each other and the spring 66 is out of engagement with the spring 59. The other terminal 30 of the magnet 37 is connected by wire 72 with the contact springs 29 and 30 of the switching mechanism and the contact spring 33 of said mechanism is connected by wire 73 with the outer ring 22 of the switching mechanism. The contact spring 32 is not connected with the wiring of the system.

35 The terminals 1 and 2 of the telephone set are connected by wires 74 and 75 with negative and positive battery supply wires 76 and 77 respectively, extending through the system from the terminals of the talking battery 78. The terminals 3 and 4 are connected by wires 79 and 80 with wires *b* and *a* of line L⁴. The terminals 5 and 6 are connected by wires 81 and 82 with positive and negative battery supply wires 83 and 84 respectively, extending through the system from the terminals of the signalling battery 85. The terminal 7 is connected by wire 86 with wire *c* of line L⁴. As a result of the connections just described, it will be observed that the wires *a* and *b* of line L⁴ are subjected to electrical potential at all 40 times from battery 78 through impedance coils 46 and 47, whether the hook 71 is in its upper or lower position. The wire *c* of line L⁴ is however, free from battery potential of any kind when the hook 71 is in its 45 lower position, since the spring 60 connected therewith is at that time free from all of the other springs of the hook switch. When the hook is raised, the spring 60 by its engagement with the spring 59, connects wire *c* with wire 84 and thus wire *c* is subjected to negative potential from the battery 85. The potential thus placed upon the wire *c* is employed to operate the lock-out mechanism at a calling station in a manner to be 50 described, if at the time the calling station attempts to connect with station 4, the latter station is engaged in conversation with another station of the system.

55 The wires *a*, *b* and *c* of line L⁵ are connected by wires 87, 88 and 89 with the inner,

the middle and the outer ones respectively of set 3 of contacts 21. Wires *a*, *b* and *c* of line L⁵ are similarly connected by wires 90, 91 and 92 with set 5 of contacts 21. Wires 79 and 80 are connected by wires 93 and 94 with the middle and inner contact rings 23 and 24 respectively of the switching mechanism. Each station thus is in permanent connection with its own line and it is not necessary to connect a line to the contacts 75 21 at its own station and when a station is called all that is necessary to do at said station to connect its line for conversation is to remove the receiver from the hook.

80 To illustrate the operation of the system and my improved mechanism, assume first that station 4 is a calling station and that the station called is not busy. The dial 13 is rotated to select the desired line, say line L⁵ and station 5, and the dial is depressed. 85 This first connects the springs 29 and 32 and at the same time connects the outer contact 21 of set 5 through switch blade 25 with ring 22, thus connecting wire *c* of line L⁵ with magnet 37 over the following path: 90 wire *c*, wire 92, contact 21, switch blade 25, ring 22, wire 73, spring 33, spring 32, spring 29, wire 72 to magnet 37. At this time there is no potential on wire *c* and there is therefore no action of the magnet to prevent 95 further inward movement of the dial. Continued movement of the dial separates the springs 32 and 33 to open the path above traced to prevent subsequently applied potential on the wire *c*, resulting from the response of the called station, reaching the magnet 37. At the same time connection is established between springs 30 and 34 the switch blades 26 and 27 connect the middle and inner contacts 21 with the rings 23 and 100 105 24 respectively for which position the dial is locked against outward movement as above described. As a result of the connection of the lines above described, lines L⁴ and L⁵ are now connected for conversation, since the 110 receiver 70 at station 4 was removed from the hook 71 before operating the switching mechanism, to prevent releasing said mechanism before the desired time. Station 5 has not yet been signalled since springs 31 and 35 115 120 are still open. To signal station 5 the dial is moved further inwards which closes springs 31 and 35 and current flows through the following path: battery 85, wire 83, wire 81, terminal 5, wire 61, spring 31, spring 35, wire 52, terminal 3, wire 79, wire 93, ring 23, switch blade 26, middle contact 21 of set 5, wire 91, to wire *b* of line L⁵, thence to and through connections at station 5 identical with the corresponding path through the 125 connections at station 4 from wire *b* of line L⁴ which may be traced as follows: wire *b* of line L⁴, wire 79, terminal 3, wire 49, bell 48, wire 67, spring 66, spring 59, wire 55, terminal 6, wire 82, wire 84 back to battery 130

85. After signalling station 5 the dial 13 is moved outward by the spring 15 to its inwardly locked position which again separates the springs 31 and 35 but does not 5 disconnect the lines. When station 5 responds by removing the receiver from the hook, the connection is in talking condition, both stations being supplied with talking current over identical paths which may be traced 10 for the station 4 as follows: battery 78, wire 77, wire 75, terminal 2, impedance coil 47, terminal 3, wire 51, primary winding 50, transmitter 63, wire 64, spring 65, spring 57, wire 53, terminal 4, impedance coil 46, terminal 1, wire 74, wire 76 back to battery 78.

15 For this condition each of the connected stations subjects wire *c* of its line to negative potential from signalling battery 85 over a similar path, which may be traced 20 for station 4 as follows: battery 85, wire 84, wire 82, terminal 6, wire 55, spring 59, spring 60, wire 56, terminal 7, wire 86 to wire *c*.

At the end of the conversation, each 25 switching mechanism is automatically released and restored to neutral or normal condition by the hanging up of the receiver at the corresponding station as follows: When the receiver 70 is placed on the hook 71, current is caused to take the following path 30 through magnet 37: battery 85, wire 83, wire 81, terminal 5, wire 61, wire 62, magnet 37, wire 72, spring 30, spring 34, wire 68, wire 67, spring 66, spring 59, wire 55, terminal 6, 35 wire 82, wire 84 back to battery 85. This energizes magnet 37 thus raising the latch 36 and releasing the plunger 12 and the spring 15 moves said plunger and parts connected therewith to their outer or neutral 40 position.

Assume now that station 4 desires to connect with either station 3 or 5 while they are 45 connected and their lines are busy. For this condition, as pointed out above, the wires *c* of lines L^3 and L^5 are subjected to negative potential from battery 85. Say that it is attempted to connect with station 5. The dial 13 at station 4 is rotated to position 5 and pressed inwards. The moment it is de- 50 pressed enough to connect the springs 29 and 32 and to connect the outer contact 21 with ring 22 through switch blade 25, current is caused to take the following path: wire *c* of line L^5 , wire 92, outer contact 21 of set 55 5, switch blade 25, ring 22, wire 73, spring 33, spring 32, spring 29, wire 72, magnet 37, wire 62, wire 61, terminal 5, wire 81, wire 83 back to battery 85. This energizes magnet 37 which at once moves the lugs 44 into 60 the path of the pin 43 and prevents further inward motion of the dial 13 and parts connected therewith and thus prevents connecting line L^4 with line L^5 . The same thing occurs on attempting to connect with any 65 busy line.

In the system shown in Fig. 5, the same general arrangement is employed as described above in connection with Fig. 1, the differences being that the lines are of the two wire type, one of the wires of each 70 line is subjected to potential only during the talking condition, and the connections at the hook switch and the construction of the switching mechanism are modified to accommodate this changed condition. In this 75 case, referring to station 4', which is the same as each of the other stations, the terminals 1 and 2 are connected as before through impedance coils with the terminals 4 and 3 respectively. Instead of being con-

80 nected with the talking battery, the terminal 1 is connected by wire 95 with spring 96 of the hook switch, which spring, when the hook is raised engages spring 97 connected by wire 98 with terminal 7, said terminal be-

85 ing connected in turn by wire 99 with wire 100, extending through the system from the negative terminal of the talking battery 78. The transmitter and induction coil primary 90 winding are connected together as before but in this case their terminals are connected directly with the terminals 3 and 4 so that when both of the terminals 3 and 4 are subjected to battery potential of opposite sign 95 current will flow through the transmitter. The terminals 3 and 4 are connected with the rings of the switching mechanism much the same as before, the only difference being that they are connected with the outer and middle rings 22^a and 23^a, instead of being 100 connected with the middle and inner rings. From the above it will appear that the terminal 4, connected through its impedance 105 coil with terminal 1, is not normally subjected to potential of any kind and that when the hook is raised, it is subjected to negative potential from battery 78^a. The terminals 3 and 4 are connected by wires 101 and 102 with wires *b* and *a* respectively of line L^4 and these wires 101 and 102 are connected by wires 103 and 104 with the rings 110 22^a and 23^a. Since there are but two wires for each line there are but two contacts 21^a in each set and these are connected at each 115 station with the line wires of the corresponding line in the same manner as before, the contacts corresponding to each station not being connected at that station to its line for the reasons pointed out above in connection with Fig. 1. The terminals 5 and 6 120 are connected as before with the exception that the terminal 5 is not connected with the hook switch which however, makes no difference in the operation of the present system. The spring contact 33^a of the 125 switching mechanism is connected by wire 107 with the inner ring 24^a of said mechanism. In other respects the connections to the switching mechanism are the same as above described.

In this case the construction of the switching mechanism is modified somewhat as shown in Fig. 6. The plunger carries switch blades 25^a, 26^a and 27^a, insulated from each other and from the plunger for engaging the rings 22^a, 23^a and 24^a respectively. In addition a fourth blade 26^b is similarly carried by the plunger. The blades 26^b and 27^a are normally in contact with each other, the blade 26^b being extended to engage the inner contacts 21^a while the blade 27^a is shorter and lies inside of the inner contacts 21^a. The blades 26^a and 26^b are normally out of contact with each other, which condition is maintained until the plunger is depressed sufficiently to bring the blade 25^a into engagement with the outer contact 21^a and the ring 22^a at which time the plunger and parts carried thereby are held in their line connecting position by the locking mechanism above described. For this condition of the mechanism, the blades 26^a and 26^b are in contact and connect the inner contact 21^a with the ring 23^a, and the blade 26^b is out of contact with the blade 27^a. In other respects the switching mechanism is of the same construction and operation as that shown in Fig. 2. With the construction shown in Fig. 6, the initial movement of the plunger to test for a busy line, connects the inner contact 21^a with the ring 24^a through blades 26^b and 27^a and thus connects the wire *a* of the called line with the wire 107 as shown in Fig. 5. If now the wire 100 from the negative side of battery 78^a is connected with said wire *a* as a result of the called line being busy, in the manner above described, the lock-out mechanism is operated by current flow over the following path: battery 78^a, wire 108, ground 109, ground connection 110, ground 111, wire 112, wire 113, wire 114, terminal 5, wire 61^a, wire 62^a, magnet 37^a, wire 72^a, spring 29^a, spring 32^a, spring 33^a, wire 107, ring 24^a, blade 27^a, blade 26^b, inner contact 21^a, wire *a* of called line and thus to wire 100 and back to battery 78^a. As a result the lock-out mechanism above described is actuated by the energizing of the magnet 37^a, and further movement of the plunger 12^a towards its line connecting position is prevented. In this case, as before, the plunger has three operating positions which follow each other progressively, first, the line testing position which operates the lock-out mechanism if the called line is busy, second, the line connecting position and third, the signalling position. In the line connecting and signalling positions of the plunger, the effect is the same as described in connection with Fig. 1, and at the end of a conversation the releasing of the switching mechanism at each station is effected in the same manner as before.

By my invention, it will be observed that I provide line wires of which at least one is

not subjected to potential if the line is not busy, which wire has potential on it when the line is busy which operates lock-out devices to prevent actuation of line connecting switching mechanism at another station, if 70 an attempt is made at the latter station to connect with the busy line; that the lock-out mechanism is a part mechanically of the switching mechanism, and more specifically that it and the releasing mechanism of the 75 switching mechanism have common operating devices; and that the lock-out mechanism may be employed either in connection with the releasing mechanism or without it as desired.

80

While I have shown my invention in the particular embodiments above described, I do not however limit myself to these constructions as I may employ any equivalents known to the art at the time of the filing of 85 this application without departing from the scope of the appended claims.

What I claim is:

1. In an intercommunicating telephone system, the combination of stations, each equipped with a telephone set, a switch hook and line connecting mechanism, lines for connecting said stations as desired, one wire of each line being free from electrical potential when not in use, a source of current, and contacts operated by the switch hook at each station for connecting said wire of the corresponding line with one terminal of said source for the busy condition of said switch hook, said mechanism comprising contacts 100 for said lines, electromagnetic devices connected with the other terminal of said source and lock-out contacts actuated by initial movement of said mechanism in attempting to connect with a busy line, for connecting 105 said wire of said line with the other terminal of said devices to actuate said devices to block completing the line connecting movement of said mechanism.

2. In an intercommunicating telephone 110 system, the combination of stations, each equipped with a telephone set, a switch hook and line connecting mechanism, lines for connecting said stations as desired, one wire of each line being free from electrical potential when not in use, a source of current, and contacts operated by the switch hook at each station for connecting said wire of the corresponding line with one terminal of said source for the busy condition of said switch 120 hook, said mechanism comprising contacts for said lines, electromagnetic devices connected with the other terminal of said source and lock-out contacts actuated by initial movement of said mechanism in attempting 125 to connect with a busy line, for connecting said wire of said line with the other terminal of said devices to actuate said devices to block completing the line connecting movement of said mechanism, continued 130

movement of said mechanism in connecting with a non-busy line opening the connection made by said lock-out contacts.

3. In an intercommunicating telephone system, the combination of stations, each equipped with a telephone set, a switch hook and line connecting mechanism, lines for connecting said stations as desired, one wire of each line being free from electrical potential when not in use, a source of current, and contacts operated by the switch hook at each station for connecting said wire of the corresponding line with one terminal of said source for the busy condition of said switch hook, said mechanism comprising contacts for said lines, electromagnetic devices connected with the other terminal of said source and lock-out contacts actuated by initial movement of said mechanism in attempting to connect with a busy line, for connecting said wire of said line with the other terminal of said devices to actuate said devices to block completing the line connecting movement of said mechanism, said devices serving to also retain said mechanism in its line connecting position on connecting with a non-busy line, and switch hook contacts and connections at the corresponding station actuating said devices on movement of said switch hook to its non-busy position to release said mechanism.

4. In an intercommunicating telephone system, the combination of stations, each equipped with a telephone set, a switch hook and line connecting mechanism, lines for connecting said stations as desired, one wire of each line being free from electrical potential when not in use, a source of current, and contacts operated by the switch hook at each station for connecting said wire of the corresponding line with one terminal of said source for the busy condition of said switch hook, said mechanism comprising contacts for said lines, a plunger, switch blades for connecting the line contacts as desired, a latch permitting initial movement of said plunger and when operated preventing further movement thereof to its line connecting position, an electromagnet for operating said latch connected with the other terminal of said source, and lock-out contacts actuated by said initial movement for connecting said wire of a busy line with the other terminal of said electromagnet to operate said latch when attempting to connect with a busy line.

5. In an intercommunicating telephone system, the combination of stations, each equipped with a telephone set, a switch hook and line connecting mechanism, lines for connecting said stations as desired, one wire of each line being free from electrical potential when not in use, a source of current, and contacts operated by the switch hook at each station for connecting said wire of the corresponding line with one terminal of said source for the busy condition of said switch hook, said mechanism comprising contacts for said lines, a plunger, switch blades for connecting the line contacts as desired, a latch permitting initial movement of said plunger and when operated preventing further movement thereof to its line connecting position, an electromagnet for operating said latch connected with the other terminal of said source, and lock-out contacts actuated by said initial movement for connecting said wire of a busy line with the other terminal of said electromagnet to operate said latch when attempting to connect with a busy line, continued movement of said plunger in connecting with a non-busy line opening the connection made by said lock-out contacts.

6. In an intercommunicating telephone system, the combination of stations, each equipped with a telephone set, a switch hook and line connecting mechanism, lines for connecting said stations as desired, one wire of each line being free from electrical potential when not in use, a source of current, and contacts operated by the switch hook at each station for connecting said wire of the corresponding line with one terminal of said source for the busy condition of said switch hook, said mechanism comprising contacts for said lines, a plunger, switch blades for connecting the line contacts as desired, a latch permitting initial movement of said

corresponding line with one terminal of said source for the busy condition of said switch hook, said mechanism comprising contacts for said lines, electromagnetic devices connected with the other terminal of said source and lock-out contacts actuated by initial movement of said mechanism in attempting to connect with a busy line, for connecting said wire of said line with the other terminal of said devices to actuate said devices to block completing the line connecting movement of said mechanism, said devices serving to also retain said mechanism in its line connecting position on connecting with a non-busy line, and switch hook contacts and connections at the corresponding station actuating said devices on movement of said switch hook to its non-busy position to release said mechanism.

7. In an intercommunicating telephone system, the combination of stations, each equipped with a telephone set, a switch hook and line connecting mechanism, lines for connecting said stations as desired, one wire of each line being free from electrical potential when not in use, a source of current, and contacts operated by the switch hook at each station for connecting said wire of the corresponding line with one terminal of said source for the busy condition of said switch hook, said mechanism comprising contacts for said lines, a plunger, switch blades for connecting the line contacts as desired, a latch permitting initial movement of said

plunger and when operated preventing further movement thereof to its line connecting position, an electromagnet for operating said latch connected with the other terminal of said source, and lock-out contacts actuated by said initial movement for connecting said wire of a busy line with the other terminal of said electromagnet to operate said latch when attempting to connect with a busy line, said latch serving to also retain said plunger in its line connecting position on connecting with a non-busy line, and switch hook contacts and connections at the corresponding station actuating said electromagnet on movement of said switch hook to its non-busy position to operate said latch and release said plunger.

8. In an intercommunicating telephone system, the combination of stations, each equipped with a telephone set, a switch hook and line connecting mechanism, lines for connecting said stations as desired, one wire of each line being free from electrical potential when not in use, a source of current, and contacts operated by the switch hook at each station for connecting said wire of the corresponding line with one terminal of said source for the busy condition of said switch hook, said mechanism comprising contacts for said lines, a plunger, switch blades for connecting the line contacts as desired, a latch permitting initial movement of said plunger and when operated preventing further movement thereof to its line connecting position, an electromagnet for operating said latch connected with the other terminal of said source, and lock-out contacts actuated by said initial movement for connecting said wire of a busy line with the other terminal of said electromagnet to operate said latch when attempting to connect with a busy line, continued movement of said plunger in connecting with a non-busy line opening the connection made by said lock-out contacts, said latch serving to also retain said plunger in its line connecting position on connecting with a non-busy line, and switch hook contacts and connections at the corresponding station actuating said electromagnet on movement of said switch hook to its non-busy position to operate said latch and release said plunger.

9. In an intercommunicating telephone system, the combination of stations, each equipped with a telephone set, a switch hook and line connecting mechanism, lines for connecting said stations as desired, each line consisting of but two wires, one wire of each line being free from electrical potential when not in use, a source of current, and contacts operated by the switch hook at each station for connecting said wire of the corresponding line with one terminal of said source for the busy condition of said switch hook, said mechanism comprising

contacts for said lines, electromagnetic devices connected with the other terminal of said source and lock-out contacts actuated by initial movement of said mechanism in attempting to connect with a busy line, for connecting said wire of said line with the other terminal of said devices to actuate said devices to block completing the line connecting movement of said mechanism.

10. In an intercommunicating telephone system, the combination of stations, each equipped with a telephone set, a switch hook and line connecting mechanism, lines for connecting said stations as desired, each line consisting of but two wires, one wire of each line being free from electrical potential when not in use, a source of current, and contacts operated by the switch hook at each station for connecting said wire of the corresponding line with one terminal of said source for the busy condition of said switch hook, said mechanism comprising contacts for said lines, electromagnetic devices connected with the other terminal of said source and lock-out contacts actuated by initial movement of said mechanism in attempting to connect with a busy line, for connecting said wire of said line with the other terminal of said devices to block completing the line connecting movement of said mechanism, continued movement of said mechanism in connecting with a non-busy line opening the connection made by said lock-out contacts.

11. In an intercommunicating telephone system, the combination of stations, each equipped with a telephone set, a switch hook and line connecting mechanism, lines for connecting said stations as desired, each line consisting of but two wires, one wire of each line being free from electrical potential when not in use, a source of current, and contacts operated by the switch hook at each station for connecting said wire of the corresponding line with one terminal of said source for the busy condition of said switch hook, said mechanism comprising contacts for said lines, a plunger, switch blades for connecting the line contacts as desired, a latch permitting initial movement of said plunger and when operated preventing further movement thereof to its line connecting position, an electromagnet for operating said latch connected with the other terminal of said source, and lock-out contacts actuated by said initial movement for connecting said wire of a busy line with the other terminal of said electromagnet to operate said latch when attempting to connect with a busy line.

12. In an intercommunicating telephone system, the combination of stations, each equipped with a telephone set, a switch hook and line connecting mechanism, lines for connecting said stations as desired, each

line consisting of but two wires, one wire of each line being free from electrical potential when not in use, a source of current, and contacts operated by the switch hook at each station for connecting said wire of the corresponding line with one terminal of said source for the busy condition of said switch hook, said mechanism comprising contacts for said lines, a plunger, switch blades for connecting the line contacts as desired, a latch permitting initial movement of said plunger and when operated preventing further movement thereof to its line connecting position, an electromagnet for operating said latch connected with the other terminal of said source, and lock-out contacts actuated by said initial movement for connecting said wire of a busy line with the other terminal of said electromagnet to operate said latch when attempting to connect with a busy line, continued movement of said plunger in connecting with a non-busy line opening the connection made by said lock-out contacts.

13. In a switching mechanism of the class described, the combination of mechanism for use at a first station for selecting and connecting with any one of a plurality of lines extending from said first station and respectively connected with other stations, whereby operation of said mechanism establishes communication directly between said first station and the other selected station, electromagnetic lock-out devices permitting initial connecting movement and when actuated preventing complete connecting movement of said mechanism, a set of line contacts for each of said lines, one contact of each set being a test contact, and means for establishing connection between said test contact and said devices by initial movement of said mechanism.

14. In a switching mechanism of the class described, the combination of mechanism for selecting and connecting lines for conversation, electromagnetic lock-out devices permitting initial connecting movement and when actuated preventing complete connecting movement of said mechanism, sets of line contacts, one contact of each set being a test contact, and means for establishing connection between said test contact and said devices by initial movement of said mechanism, continued movement of said mechanism when said devices are not operated interrupting said connection.

15. In a switching mechanism of the class described, the combination of sets of contacts for lines to be connected, a plunger, switch blades carried by said plunger for connecting said contacts as desired, one contact of each set being a test contact, a latch

permitting initial movement of said plunger and when actuated preventing complete connecting movement of said plunger, an electromagnet for actuating said latch, and contacts actuated by initial movement of said plunger for connecting said test contact with said electromagnet.

16. In a switching mechanism of the class described, the combination of sets of contacts for lines to be connected, a plunger, switch blades carried by said plunger for connecting said contacts as desired, one contact of each set being a test contact, a latch permitting initial movement of said plunger and when actuated preventing complete connecting movement of said plunger, an electromagnet for actuating said latch, and contacts actuated by initial movement of said plunger for connecting said test contact with said electromagnet, continued movement of said plunger when said latch is not actuated interrupting said last named connection.

17. In a switching mechanism of the class described, the combination of mechanism for selecting and connecting lines for conversation, electromagnetic lock-out devices permitting initial connecting movement and when actuated preventing complete connecting movement of said mechanism, sets of line contacts, one contact of each set being a test contact, and means for establishing connection between said test contact and said devices by initial movement of said mechanism, said devices also serving to retain said mechanism in its line connecting position.

18. In a switching mechanism of the class described, the combination of sets of contacts for lines to be connected, a plunger, switch blades carried by said plunger for connecting said contacts as desired, one contact of each set being a test contact, a latch permitting initial movement of said plunger and when actuated preventing complete connecting movement of said plunger, an electromagnet for actuating said latch, and contacts actuated by initial movement of said plunger for connecting said test contact with said electromagnet, said latch also serving to retain said plunger in its line connecting position.

19. In a switching mechanism of the class described, the combination of sets of contacts for lines to be connected, a plunger, switch blades carried by said plunger for connecting said contacts as desired, one contact of each set being a test contact, a latch permitting initial movement of said plunger and when actuated preventing complete connecting movement of said plunger, an electromagnet for actuating said latch, and contacts actuated by initial movement of said plunger for connecting said test contact with said electromagnet, said latch also serv-

ing to retain said plunger in its line connecting position, and said electromagnet then serving when energized to withdraw said latch and release said plunger.

- 5 20. In a switching mechanism of the class described, the combination of mechanism for selecting and connecting lines for conversation, electromagnetic lock-out devices permitting initial connecting movement and 10 when actuated preventing complete connecting movement of said mechanism, sets of line contacts, each set consisting of but two contacts, one contact of each set being a test contact, and means for establishing connection between said test contact and said devices by initial movement of said mechanism.
- 15 21. In a switching mechanism of the class described, the combination of mechanism for selecting and connecting lines for conversation, electromagnetic lock-out devices permitting initial connecting movement and when actuated preventing complete connecting movement of said mechanism, sets of line 25 contacts, each set consisting of but two contacts, one contact of each set being a test contact, and means for establishing connection between said test contact and said devices by initial movement of said mechanism, continued movement of said mechanism when said devices are not operated interrupting said connection.

- 30 22. In a switching mechanism of the class described, the combination of sets of contacts for lines to be connected, each set consisting of but two contacts, a plunger, three switch blades carried by said plunger for connecting said contacts as desired, one of said blades being a test blade and the other

blades being line connecting blades, said test 40 blade being in contact with one of the other blades when the plunger is in its outer and test positions, one contact of each set being a test contact, a latch permitting initial movement of said plunger and when actuated 45 preventing complete connecting movement of said plunger, an electromagnet for actuating said latch, and contacts actuated by initial movement of said plunger for connecting said test contact with said electro- 50 magnet.

23. In a switching mechanism of the class described, the combination of sets of contacts for lines to be connected, each set consisting of but two contacts, a plunger, switch 55 blades carried by said plunger for connecting said contacts as desired, one of said blades being a test blade and the other blades being line connecting blades, said test blade being in contact with one of the 60 other blades when the plunger is in its outer and test positions, one contact of each set being a test contact, a latch permitting initial movement of said plunger and when actuated 65 preventing complete connecting movement of said plunger, an electromagnet for actuating said latch, and contacts actuated by initial movement of said plunger for connecting said test contact with said electro- 70 magnet, continued movement of said plunger when said latch is not actuated interrupting said last named connection and separating said test blade from contact with the adjacent line connecting blade.

In witness whereof, I hereunto subscribe 75 my name this 12th day of October, A. D. 1918.

THEODORE H. NELSON.
